US00D615590S

(12) **United States Design Patent**
Li

(10) **Patent No.:** US D615,590 S
(45) **Date of Patent:** ** May 11, 2010

(54) **PEN**

(75) Inventor: **Bin Li**, Ningbo (CN)

(73) Assignee: **Beifa Group Co., Ltd.**, Ningbo (CN)

(**) Term: **14 Years**

(21) Appl. No.: **29/333,928**

(22) Filed: **Mar. 17, 2009**

(30) **Foreign Application Priority Data**

Sep. 19, 2008 (CN) 2008 3 0147530

(51) **LOC (9) Cl.** 19-06

(52) **U.S. Cl.** D19/51

(58) **Field of Classification Search** ..... D19/35, D19/36, 41, 42, 43, 44, 45, 46, 47, 48, 49, D19/50, 51, 54, 55, 56, 57; 24/11 F, 11 P, 24/11 R; 401/6, 52, 99, 100, 104, 105, 106, 401/107, 108, 109, 192, 195, 243, 244, 245, 401/246, 247

See application file for complete search history.
